RAZOR

Eugene M. Perkins, Boston, Mass.

Application October 14, 1944, Serial No. 558,681

13 Claims. (Cl. 30—53)

This invention relates to razors and more particularly to safety razors of the class in which the blade has a thickened rear portion to which a handle, either for shaving or for stropping and honing, may be attached. In other words, the invention relates to razors of the class disclosed in U. S. Patent No. 2,357,601, issued to me September 5, 1944. One such razor is the Rolls, in which the thickened rear portion of the blade is provided with a socket having internal projections arranged to interlock with projections on a stud carried by a handle.

The machining of the socket with its internal projections is a difficult and relatively costly operation. The same is true of the stud. The present invention is concerned with a novel and improved construction in which the socket or bearing in which the stud or pivot turns is without any internal projections, and in practice is merely a drilled hole, much less difficult and costly to produce than one with internal projections.

The invention will be understood by reference to the following description when taken in connection with the accompanying drawing of some specific embodiments thereof, while its scope will be pointed out more particularly in the appended claims.

In the drawing:

Fig. 1 is a plan of a razor embodying the invention;

Fig. 2 is an elevation partly in section on line 2—2 of Fig. 1;

Fig. 3 is a sectional view on the irregular line 3—3 of Fig. 2;

Fig. 4 is a sectional view on line 4—4 of Fig. 2;

Fig. 5 is an elevation partly in section of a modification;

Fig. 6 is an elevation partly in section of a second modification;

Fig. 7 is a sectional view on line 7—7 of Fig. 6;

Fig. 8 is a plan of a third modification;

Fig. 9 is an elevation of the same;

Fig. 10 is an elevation viewed from the right-hand side of Fig. 9; and

Fig. 11 is a sectional view on line 11—11 of Fig. 10.

Referring to the drawing and to the embodiment of the invention illustrated in Figs. 1 to 4 inclusive, there is shown an example in which a blade 12 is provided with a cutting edge 14 and a thickened rear portion 16 which serves for the attachment of a handle 18 by novel means now to be described, reference being had at first more particularly to Fig. 2.

The connection between the blade and the han-

dle includes a pivot 20, preferably cylindrical, and a bearing 22 therefor which is simply a drilled hole and hence easily and inexpensively machined. In this example the hole is inclined to the cutting edge, and advantage is taken of this fact to hold the pivot in place in its bearing in the manner presently to be explained.

The handle is connected to the pivot by a shank 24, which normally interengages with the blade to resist turning of the pivot in its bearing. In this example, this is conveniently accomplished by making the shank with a rounded, or cylindrical, portion 26 normally received in a depression 28 in the blade. The shank has a relatively thinner, flexible or resilient portion 30 capable of springing and thus permitting the portion 26 of the shank to rise out of the depression 28 when sufficient force is applied to swing the handle 18 about the axis of the pivot 20. Conversely, when restoring the handle to its normal position, one or two inclined ramps 32 (see Fig. 4), herein two ramps at opposite sides of the depression 28, cause the resilient portion 30 to flex and the portion 26 to rise and ride up the ramp and then snap into the depression 28.

From a comparison of Figs. 2 and 3, it will be observed that the pivot 20 is at an obtuse angle to the handle and that owing to this obtuse angle, in swinging from the position shown in Fig. 3 to which the pivot can be withdrawn from the bearing to the normal position shown in Fig. 2, the shank portion 26 descends as it swings and encounters one of the ramps 32. At this stage the pivot 20 should be held firmly in the bearing 22 as the portion 28 of the shank 24 rides up the ramp and then snaps into the depression 28.

When this position is reached, the handle is held securely attached to the blade by reason of the angularity of the pivot and its bearing and by reason of the fact that the handle cannot swing about the axis of the pivot. The handle may therefore be made use of in honing or stropping the blade. In the case of a handle for shaving (see Figs. 8 to 11 inclusive) similar construction is employed, the handle and the blade with its angular bearing and the pivot turning therein, as well as the depression and the ramps, are the same as before, but the depression receives a resilient arm 34 which projects laterally from the shank.

While the described arrangement including the angular pivot and bearing suffices in and of itself and without other aid to accomplish the attachment of the handle to the blade when the pivot 20 is pressed inwardly during assembly, there may

be added means to make such pressure unnecessary as by a lip 36 above the pivot and underlying a shoulder 38 above the bearing (see Fig. 5) or by a laterally rounded lug 40 entering a notch 42 to prevent the pivot from backing out of the bearing without actually pressing the pivot inwardly at the instant of interlock of the shank with the blade. By comparing the axis A—A of the pivot with the line B—B parallel therewith, it will readily be understood that the right-hand corner of the notch 42 presents a barrier at the right-hand end of the lug 40, preventing the pivot from rising in its bearing.

Having thus described these several embodiments of the invention, what I claim is:

1. In a razor, the combination of a blade provided with a bearing whose axis is inclined to the cutting edge, a pivot turning in said bearing, a member which rotates said pivot in said bearing, and interengaging means on said blade and carried by said member normally to resist said turning, and a resilient connection between said pivot and said member normally tending to change their angular relationship and to thrust said member toward said blade.

2. In a razor, the combination of a blade provided with a bearing whose axis is inclined to the cutting edge, a pivot turning in said bearing, a member which rotates said pivot in said bearing, said member being at an obtuse angle to said pivot, means carried on said member and said blade tending to resist said turning, and resilient means connecting said member to said pivot and normally under stress tending to reduce said angle to a less obtuse angle.

3. In a razor, the combination of a blade provided with a bearing whose axis is inclined to the cutting edge, a pivot turning in said bearing, a handle which rotates said pivot in said bearing, and an arm carried by said handle and normally interengaging with said blade to resist turning of said pivot and said handle about the axis of said pivot.

4. In a razor, the combination of a blade provided with a bearing whose axis is inclined to the cutting edge, a pivot turning in said bearing, a handle which rotates said pivot in said bearing, and an arm carried by and disposed transversely of said handle and normally interengaging with said blade to resist turning of said pivot and said handle about the axis of said pivot.

5. In a razor, the combination of a blade provided with a bearing whose axis is inclined to the cutting edge, said blade being provided also with a depression radial to the axis of said bearing, a pivot turning in said bearing, a handle which rotates said pivot in said bearing, and an arm carried by said handle and normally received in said depression to resist turning of said pivot and said handle about said axis.

6. In a razor, the combination of a blade provided with a bearing whose axis is inclined to the cutting edge, said blade being provided also with a depression radial to the axis of said bearing, a pivot turning in said bearing, a handle which rotates said pivot in said bearing, and an arm projecting laterally with relation to said handle and normally interengaging with said blade.

7. In a razor, the combination of a blade pro-

vided with a bearing whose axis is inclined to the cutting edge, a pivot turning in said bearing, a member which rotates said pivot in said bearing, said member being at an obtuse angle to said pivot, interengaging means on said blade and member and extraneous to said bearing normally to resist turning of said member about said axis as well as movement of said pivot from said bearing, and a resilient connection between said pivot and said member normally under stress tending to reduce said angle to a less obtuse angle.

8. In a razor, the combination of a blade provided with a bearing whose axis is inclined to the cutting edge, a pivot turning in said bearing, a member which rotates said pivot in said bearing, said member being at an obtuse angle to said pivot, interengaging means on said blade and member and disposed remotely from said pivot and said bearing, normally to resist turning of said member about said axis as well as movement of said pivot from said bearing, and resilient means between said pivot and said member normally under stress tending to reduce said angle to a less obtuse angle.

9. In a razor, the combination of a blade provided with a bearing transverse to the cutting edge, a member carrying a pivot turning in said bearing, and means extraneous to said bearing and to said pivot and normally interlocking laterally of the pivotal axis to prevent withdrawal of said pivot from said bearing, said means having provision for relative rotation to another position in which said pivot may be withdrawn from said bearing.

10. In a razor, the combination of a blade provided with a bearing transverse to the cutting edge, a pivot arranged to turn in said bearing, a member by which said pivot is rotated, a lip on said blade externally of said bearing, and a lip carried by said member externally of said bearing and normally underlying the first-named lip and arranged to pass from beneath the first-named lip during rotation of said pivot from its normal position.

11. In a razor, the combination of a blade provided with a bearing whose annular surface is cylindrical, a pivot whose annular surface is correspondingly cylindrical, a handle which turns said pivot in said bearing, and means between said pivot and said handle normally to maintain said pivot in said bearing.

12. In a razor, the combination of a blade provided with a bearing whose annular surface is cylindrical, a pivot whose annular surface is correspondingly cylindrical, a handle which turns said pivot in said bearing, and resilient means between said pivot and said handle normally to maintain said pivot in said bearing.

13. In a razor, the combination of a blade provided with a bearing whose annular surface is cylindrical, a pivot whose annular surface is correspondingly cylindrical, a handle which turns said pivot in said bearing, means normally to prevent turning of said pivot and said handle, and resilient means normally under stress tending to prevent retraction of said pivot from said bearing.

EUGENE M. PERKINS.
